UNITED STATES PATENT OFFICE.

MICHAEL W. McARDLE, OF CHICAGO, ILLINOIS

RAZOR STROP.

Application filed January 28, 1926. Serial No. 84,269.

The purpose of this invention is to provide an improved and simplified form of device for sharpening blades, such as safety razor blades, which can be collapsed into compact form for carrying in the pocket or toilet case. It consists in the elements and features of construction shown and described as indicated in the claims.

In the drawings:—

10 Figure 1 is a perspective view of a device embodying this invention in the form for use, and illustrating the manner of handling the strop and the blade in sharpening the latter.

15 Figure 2 is a rear side elevation of the device collapsed for storing when out of use.

Figure 3 is a section at the line 3—3 on Figure 2 showing, however, the handle set at operating position as in Figure 1 instead of folded into collapsed position as in

Figure 2.

Figure 4 is a front side elevation of the device collapsed.

20 Figure 5 is a detail section on an enlarged scale of the extensible and collapsible connection between the ends of the strop plate for flexing the latter, showing the same at contracted position.

25 Figure 6 is a sectional direct side elevation of the implement with the strop blade flexed in form for use, section being made at the middle part of the length of the contractile and extensible connection through the locking feature.

30 Figure 7 is a section at the line 7—7 on Figure 6.

The implement shown in the drawings comprises a spring plate, 10, adapted to be flexed as shown in Figures 1 and 6 into approximately half cylindrical form, and to react from such flexure to its normal straight or flat form, said spring plate having at the side which is flexed convex for service, covered with a strop leather, 11, or in any way suitably surfaced for sharpening a blade. The opposite ends of the spring plate are connected together by an extensible and contractile connection consisting, as shown, of two interlocking slides, 12 and 13, whose interlocking is effected by folding the lateral margins of the slide, 12, over the corresponding margins of the slide, 13, as may be seen in Figure 7, the remote ends of the two slides being hinged to the opposite ends respectively of the spring plate, 10, as may be understood most clearly from Figures 5 and

6. The interlocked slides are dimensioned longitudinally forlapping upon each other a distance nearly half the length of each when they are extended so as to lie flat upon the back side of the straight-extended spring plate as seen in Figure 3.

The outer slide, 12, has an aperture, 14, near its hinged end as seen in Figure 5, and the inner slide, 13, is slotted as indicated at 15, 15, to form a tongue, 16, whose free end is reflexed upon itself as seen at 17, forming a protrusion from the under side of the tongue which is dimensioned for engaging the aperture, 14, in the slide, 12, this engagement occurring when the slides are interlocked to the full extent contemplated for drawing toward each other the opposite ends of the spring plate for flexing the latter to the curved condition for service as shown in Figure 1.

Upon the outer or back side of the outer slide, 1, there is pivotally mounted a stirrup or offset bracket, 20, for carrying a handle, 21. The handle is secured to the stirrup by means of a headed bolt, 22, which is screwed through a suitably threaded aperture in the bracket, 20, and at the same time screwed into the end of the handle for permanent connection to the latter. The under side of the head, 22^a, of the bolt when the latter is screwed in permanent position into the handle is spaced from the end of the handle a distance in excess of the thickness of the bracket through which it is screwed by an amount somewhat greater than the aggregate thickness of the two slides, 12 and 13, and the height or axial dimension of said head is approximately equal to the space between the inner side of the bracket and the slide, 12, as may be understood from Figure 3. The slide plate, 12, to which the bracket is pivoted has an aperture, 12^b, in alignment with the head of the bolt when the handle is extended perpendicular to the slides for use of the device as seen in Figures 1 and 3; and the slide, 13, has an aperture, 13^b, which registers with the aperture, 12^b, when the slides are interlocked for contracting the connection which they form between the ends of the spring plate for flexing the latter to form for service; that is to say, at the interlocked position at which the tongue, 16, of the inner slide, 13, engages the aperture, 14, of the slide, 12, as seen in Figure 5; and when the slides are thus interlocked and locked for flexing the spring and strop sur-

face, the handle having been swung from position shown in Figure 2 flat against the back side of the slides—to position it perpendicular to the slides as seen in Figures 1 and 3, the handle is screwed in through the bracket to thrust the head 22^a of the bolt, 22, through the registered apertures, 12^b and 13^b of the slides, thereby, first and primarily, securing the handle in its perpendicular position with respect to the slides, and secondly, securely locking the slides at interlapped and contracted position, supplementing in this respect the service performed by the engagement of the tongue, 13^b, of the slide, 13, with the aperture, 12^b, of the slide, 12.

The mode of operation and use of the device will be understood from the foregoing description of the construction without further explanation.

I claim:

1. An implement for the purpose indicated and the like, comprising in combination a spring plate surfaced at one side for sharpening purposes, and adapted to be flexed convex at that side; slidably engaged slides having their remote ends hinged respectively to the opposite ends of the spring plate, and extending at the opposite side of said plate, and means for locking said slides at contracted position for holding the plate flexed.

2. An implement for the purpose indicated and the like comprising in combination a spring plate surfaced at one side for the service desired and adapted to be flexed convex at that side, means for so flexing it comprising an extensible and contractible connector consisting of slidably engaged slides having their remote ends engaged respectively with the opposite ends of the spring plate and extending at the opposite side of said plate; a handle mount pivoted to the outer of said slides and a handle extending from said mount for folding into position parallel with the spring plate at the extended flat position of the latter, and

adapted by the pivoting of the mount to be set perpendicular to the spring plate, said outer slide having an aperture aligned with the handle at the perpendicular position of the latter, the handle having a terminal and being adapted to be screwed through the mount for engaging said terminal in said aperture for locking the handle at said perpendicular position.

3. In the construction defined in claim 2, the inner slide having an aperture positioned for registering with the aperture in the outer slide at the contracted position of said slides, and the terminal of the handle being dimensioned for extending into said aperture when screwed into the aperture of the outer slide, whereby the handle at said perpendicular position serves to lock the slides at contracted position.

4. An implement for the purpose indicated and the like comprising a spring plate having a strop leather mounted upon one face and adapted to be curved convex at that face; interlocking slides hinged at their opposite ends to the opposite ends of the spring plate for extending along the side of the latter opposite the strop leather and interlocked upon each other when thus extended upon the spring plate at straight extended position of the latter, the outer-lapped slide having at its outer side a mount for a handle and an aperture opposite said mount, the handle being engaged with the mount for alignment with the aperture for protruding thereinto, the inner slide having an aperture positioned for registering with the first mentioned aperture when the slides are interlocked for shortening the connection between their opposite ends and bowing the spring plate, and the handle being adapted to be thrust through the registered apertures for locking the slides at interlocked and spring-plate bowing position.

In testimony whereof I have hereunto set my hand at Chicago, Illinois, this 25th day of January, 1926.

MICHAEL W. McARDLE.
